ELECTRIC TERMINAL BOX

Raoul Fima, 655 W. Diversey, Addison, Ill. 60101, and
Andrew L. Alger, 230 Maple Ave., Wilmette, Ill.
60091

Filed Sept. 29, 1975, Ser. No. 617,829

Term of patent 14 years

Int. Cl. D13—03

U.S. Cl. D26—5 B

FIG. 1

FIG. 2

FIG. 3

FIG. 4

FIG. 5

FIG. 6

FIG. 1 is a perspective view of an electric terminal box showing my new design;

FIG. 2 is an enlarged perspective view thereof, the cover open for purposes of disclosure;

FIG. 3 is an enlarged fragmentary top plan view thereof, the cover being broken away for purposes of disclosure;

FIG. 4 is an enlarged fragmentary front elevational view thereof, the wall of the bay being broken away for purposes of disclosure;

FIG. 5 is an enlarged fragmentary side elevational view thereof, the wall of the box being broken away for purposes of disclosure; and

FIG. 6 is an enlarged bottom plan view thereof.

We claim:

The ornamental design for an electric terminal box, substantially as shown and described.
